OUTBOARD MOTOR SUPPORT

Russell H. Harneit, New Rochelle, N. Y.

Application December 18, 1950, Serial No. 201,263

2 Claims. (Cl. 248—4)

1

This invention pertains to an outboard motor support designed for use in combination with a conventional boat having a main driving motor or power unit and a conventional steering rudder rather than to a support for an outboard motor where the outboard is the main and sole driving means for the boat.

Accordingly, the present invention provides a secondary or emergency power means to enable a conventional boat to return to port when its main power plant is disabled and inoperative.

The primary object of the invention is the provision of an outboard motor support which is quickly and easily attached to or detached from the transom of a boat.

A further object of the invention is an outboard motor support which can be raised and lowered vertically to permit the motor to be lifted clear of the water and conveniently positioned for cranking or starting by the usual means employed and to also position the motor where it can be conveniently refueled by a person on the boat.

A still further object of the invention is to provide an outboard motor support having thereon means for locking the steering handle of the motor so that the rudder, which forms a part of the motor unit, can be locked or secured in a neutral position so that the boat can be steered by its conventional rudder.

A still further object of the invention is to provide an outboard motor support embodying a motor supporting platform which is adjustable to position the motor toward or away from the boat transom and is adjustable about a horizontal pivot so that the motor propeller may be positioned at selective inclinations to the vertical.

A still further object of the invention is the provision of an outboard motor which can in part be collapsed and in part quickly assembled or dis-assembled so that it may be stored in a minimum space.

Other objects and advantages of the invention will appear from the following description when read in the light of the accompanying drawings.

In the drawings:

Fig. 1 is a side elevation illustrating the device mounted on the stern or transom of a boat.

Fig. 2 is a perspective view of the support, illustration of the motor being omitted.

Fig. 3 is a front view of the guideways of the support, the parts being illustrated in a partially collapsed position.

Fig. 4 is a detailed perspective view of the hinge joint of the guideway braces, the hinge being closed.

2

Fig. 5 is a view similar to Fig. 4 with the hinge being shown in an open position.

Fig. 6 is a horizontal sectional view on the lines 6—6 of Fig. 2 looking in the direction indicated by arrows.

Fig. 7 is a fragmentary top plane view illustrating the holding clip for the steering handle of the motor.

Fig. 8 is a vertical sectional view on the line 8—8 of Fig. 7.

Fig. 9 is a fragmentary top view illustrating the construction which gives adjustability to the side frames and braces of the support platform.

Having reference now to the drawings and 15 utilizing like reference numerals and characters to designate similar parts, A is the stern end of a conventional boat provided with a conventional boat drive means and steering rudder, neither of which is illustrated and having the usual and 20 conventional transom 1. The rudder of a conventional boat is ordinarily under the stern and would not be visible.

A pair of elongated guides B and C are interconnected adjacent their upper and lower ends 25 by a pair of hinged cross braces D and E. These braces are identical in construction and each comprises arms 2 and 3 having outer ends suitably pivotally connected to the rear faces of the guides while their inner ends are pivotally connected to one another at 4. To assure rigidity

30 when the hinge is closed and to provide frictional engagement between the pivotally connected ends 2 and 3 the brace part 3 is cut-out as at 5 for frictional telescopic reception of a tongue 6 carried by the brace part 2. When the hinges of the 35 braces are closed the guides are positioned in spaced parallel relationship, as in Fig. 2, but when the hinges are open the guides can be folded or collapsed so that their opposing side faces are in abutment. This permits this part of 40 the support to be stowed in a limited space which is of course advantageous on a boat.

At their upper ends guides B and C are provided with hooks 7 and 8 which attachably engage eyes 9 which extend outwardly from the 45 boat transom 1. At their lower ends the guides carry a similar set of hooks one of which is illustrated and is designated 10. A second set of eyes 11 extend rearwardly from the boat transom for the reception of these hooks. When the 50 hooks of the guides are engaged with the eyes the guides extend vertically and are disposed and held in spaced apart parallel relationship.

The outer or rear face of each guide is provided 55 with a T-shaped guideway which are designated 12 and 13 respectively. T-shaped slides F and

G are disposed in the guideways and vertically slideable therein. Adjacent their lower ends the guideways are provided with stops 14 and 15 which engage the lower ends of the slides and limit their lower most movement.

A platform is made up of side arms P and H, a rear end J and a cross brace 16. Each of the side arms comprise a pair of elements 17 and 18 having overlapping ends, see Fig. 9, which are secured together by a pair of thumb bolts or nuts 19 and 20 which are selectively positioned through two of a plurality of holes provided in the over-lapping ends of the elements 17 and 18. The inner ends of the elements 18 are pivotally connected to the slides F and G as at 21 and 22.

A pair of side supporting braces K and L are each made up of two pieces 23 and 24. Pieces 23 are pivotally connected to the slides as at 25 and the pieces 24 are pivotally connected to the platform side arms as at 26. The pieces 23 and 24 have over-lapping ends each provided with a plurality of bolt holes 27 for the reception of pairs of wing nuts similar to those described and illustrated in Fig. 9. To add rigidity the slides F and G are interconnected across their upper ends by a cross brace or bar 28.

The outboard motor is designated as an entirety by M and embodies the usual steering handle 29, rudder 30 and propeller 31 and a clamp 32.

The rear-end J of the platform in reality constitutes a block for the reception of the outboard motor clamp 32 as appears in Fig. 1. By reason of the pivotal connections 21 and 22 of the side arms of the platform and the adjustability of the lengths of the supporting braces K and L the outer end of the platform can be raised and lowered by varying the lengths of K and L. This adjustment makes it possible to tilt the outboard motor so as to dispose the propeller thereof at the most desirable angle to obtain proficiency of drive.

As is well known, an outboard driven boat is usually steered by rotating the outboard motor about a vertical axis. In the present instance the steering of the boat is to be done by the conventional boat rudder and to avoid interference with proper steering the rudder 30 of the outboard motor should be held in a neutral, that is non-steering, position. To accomplish this the steering handle of the motor should be locked with the rudder 30 positioned in alignment with the longitudinal axis of the boat. A clip lock N is provided for engaging and so locking the steering handle of the motor. This clip is secured to the platform side supporting brace K as at 33. The clip embodies a rigid wall 34 and a resilient wall 35 which are spaced apart and interconnected at their lower ends by bottom wall 36. The construction provides a socket or channel-way for resiliently and frictionally engaging and holding steering handle 29 in the manner clearly illustrated in Figs. 7 and 8.

Adjacent its upper end the guide 13 is provided with a rearwardly extending arm 37 and the guide G with an oppositely positioned rearwardly extending arm 38. These arms receive and support a readily removable rod 39. In Fig. 1 the platform and motor are illustrated in an elevated position. The parts are supported in this

position by the use of the rod 39 which extends beneath the side arms H and P of the platform. The lowered position of the platform is illustrated in dotted lines in Fig. 1. When so positioned the lower ends of the slides F and G are in engagement with the stops 14. When the platform is in an elevated position the motor is conveniently positioned to be started or refueled from the boat and it is possible to start the motor without it being under load.

To facilitate storage in a limited space the pivotal connections 21 and 22 are in the form of bolts with wing nuts as are also the pivotal connections 25. Thus the platform can be easily and quickly disconnected from the slides. The pivotal connections 26 are of a similar nature and thus the supporting side braces K and L can be quickly disconnected from the platform. Removal of the pivots 25 disconnects the cross-bar 28 from the slides. In its dismantled state the support will require a minimum of space for storage.

What I claim is:

1. In a device for quickly in its entirety attaching to or detaching from a boat a support and carrier for an outboard propelling motor, a pair of elongated guide elements each of which is provided in its front face with a longitudinally extending guideway, a hook on the rear face of each guide element adjacent each of its ends and adapted to attach the guides to the boat with the guides extending vertically and in spaced parallel relationship; an elongated slide disposed in each guideway for vertical sliding movement therein, a substantially horizontally disposed platform secured to and extending rearwardly from the lower ends of the slides, braces extending from adjacent the outer rear corners of the platform to the upper ends of the slides, a brace interconnecting the upper and lower ends respectively of the guide elements, said braces in addition to said hook attachment of the guides to the boat serving to add rigidity to the said positioning of the guides.

2. A construction as defined in claim 1 wherein the braces interconnecting the upper and lower ends of the guide elements are in the form of hinges which permit the guides to be moved into side to side abutting relationship when the guides are removed from the boat.

RUSSELL H. HARNEY.
